Atty.*

UNITED STATES PATENT OFFICE.

THOMAS H. MARS, OF CHICAGO, ILLINOIS, ASSIGNOR TO SUPERIOR ENGINEERING COMPANY, A CORPORATION OF ILLINOIS.

PUMP.

Application filed October 20, 1926. Serial No. 142,833.

This invention generally appertains to pumps and particularly to a double acting force pump for raising liquids.

The invention purposes to provide an im-

proved pump of this character in which pressure and vacuum losses will be reduced to a minimum if not entirely overcome, thereby materially enhancing the efficiency thereof.

10 Another purpose is to provide a simplified construction which lends itself to quantity production at a low cost.

Other objects, more specific, are to provide a novel form of piston actuating mechanism; to provide an improved casing for the pump; and to provide a construction in which leakage of the pumped liquid is prevented.

Undoubtedly other objects will be apparent to those skilled in this art as the description of the invention continues.

Briefly, these desirable objects are attained in a double acting reciprocatory, piston force pump by providing a novel casing in which the improved pump structure is arranged in the most advantageous manner.

Reference should now be made to the accompanying sheet of drawings illustrating one practicable embodiment which this invention may assume in practice, and in which,—

Figure 1 is a longitudinal, vertical sectional view of the pump, taken along the section line 1—1 of Figure 2, as viewed in the direction of the arrows; and

Figure 2 is a similar view, partly in section and at right angles to the view shown in Figure 1, as seen along the section line 2—2 of Figure 1, looking in the direction of the arrows.

In these drawings it will be seen that the improved pump embodies a novel casing made up of two identical complementary sections 5 and 6, whose abutting edges are securely held together by bolts 7. The terminal ends of these sections are formed with complementary portions forming nipples 8 which are threaded to receive a nut 9 for holding the ends of the casing sections to-

gether. These nuts 9 are provided with a threaded bore, as shown, and these bores receive at one end an intake lead 10 and at the other end, a discharge lead 11.

Centrally disposed on the inside of the casing sections are complementary portions 55 forming a sleeve 12 transversely arranged in the casing. This sleeve extends almost the width of the casing, but stops just short of the casing walls at its ends for a purpose presently to appear. This sleeve 12 carries 60 therein for reciprocation a double acting piston 13 having a head at each end, which heads are securely held together by bolts 14. It will be noted that the inner side of each head has formed therein an elongated 65 dwell or cam track 15 for a purpose later to appear. Piston rings 16 are provided to form a tight pressure seal between the piston 13 and sleeve 12.

Looking at the casing structure again 70 (Figure 2), it will be seen that the two complementary sections 5 and 6 are formed to provide nipples 17, each formed with a bore to receive a journal bushing 18, which bushings serve as a journal for a shaft 19. 75 The bushings 18 may be held in place by dust proof caps 20, as will be understood. It will be observed that the shaft 19 extends transversely through the piston 13 at a right angle. One end of the shaft 20 protrudes through the casing, as shown, and is squared, detachably to receive a hand crank 21. If desired, packing rings 22 may be placed around the shaft 19 to insure against leakage or pressure losses adjacent the journals of the shaft, but in practice these washers will probably be unnecessary, as will later be understood.

The shaft 19 integrally has formed thereon, centrally in the casing, an eccentric 23 80 which carries a ball bearing 24, whose inner race is fitted on the eccentric and whose outer race rides in the dwells 15 formed on the inner face of the heads of the piston.

The central disposition of the sleeve 12 in 85 the casing leaves an intake chamber 25 at one end of the casing and an exhaust chamber 26 at the other end. Oppositely dis-

posed in the intake chamber are blocks 27 in which are formed ports 28, each provided with a spring pressed poppet valve 29. These valves are intake valves. Similarly, at the other end of the casing are blocks 30, ports 31, and spring pressed poppet valves 32, which latter are exhaust valves.

In operation, it can now be seen that either rotation or rocking of the shaft 19 by means of the hand crank 21 will cause the piston 13 to be reciprocated in the sleeve 12, by means of the eccentric drive described. As viewed in Figure 1, movement of the piston to the right will cause a vacuum at the left of the casing, which will suck open the left hand intake valve 29, causing liquid to be drawn up into the chamber 27. At this step, the right hand intake valve 29 will be kept closed, as is apparent. A return movement of the piston to the left will now force the liquid upwardly around the left hand end of the piston and out the left hand discharge valve 32, because this pressure seats the left hand valve 29, while at the same time it will create a vacuum which will suck open the right hand intake valve 29 to draw up more liquid. Thus, the alternate pressures and vacuums will control the valves alternately, and force a constant stream of liquid out through the exhaust lead 11, as will be understood.

It is very important to observe that the path of the liquid through the pump casing is alternately around the head ends of the piston, which paths are as remote as possible spaced away from the joint between the two casing sections 5 and 6, and the journals 18 for the shaft 19. Thus, the liquid never streams past the joints or journals in the body of the casing, thereby preventing leakage. The piston rings 16 similarly prevent the liquid from getting into the driving parts. Furthermore, the pressure and vacuum strokes of the piston 19 are against the faces of the casing sections, also as remote as possible spaced away from the joints between the sections and the journals of the shaft, which construction effectually prevents pressure and vacuum losses, thereby materially increasing the efficiency of the pump.

Another important feature in the efficient operation of this pump is the dwell formation 15 of the piston in which the bearing 24 rides up and down, because of the eccentric drive. The dwell, being like a cam track, causes the bearing to function like a tractor in positively moving the piston, with frictional resistance cut to a minimum.

From the above disclosure it can now be appreciated that all of the objects heretofore expressed are accomplished. It is to be understood that the present disclosure is purely illustrative and may assume other forms in practice, and that it is the intention

to cover all changes and modifications which do not depart from the spirit and scope of this invention as is indicated in the subjoined claims.

What I claim is:

1. A pump comprising a casing provided with inlet and outlet leads, said casing also having a sleeve arranged therein, a piston in the sleeve, means for reciprocating the piston comprising a rotatable shaft and an eccentric, said shaft passing at a right angle through said piston and an anti-friction bearing between the eccentric and piston. 75

2. A pump comprising a casing provided with inlet and outlet leads, said casing also having a sleeve arranged therein, a double headed piston in the sleeve, a shaft extending through the piston between its heads, an eccentric formed on the shaft for reciprocating the piston, and an anti-friction bearing between the eccentric and heads of the piston. 85

3. A pump comprising a casing provided with inlet and outlet leads, said casing also having a sleeve arranged therein, a double headed piston in the sleeve, a shaft extending through the piston between its heads, a cam track on the inner face of each piston head, an eccentric formed on the shaft, and an anti-friction bearing movable in the cam tracks between the piston heads and eccentric. 95

4. A pump comprising a casing provided with inlet and outlet leads, said casing also having a sleeve formed therein, a double headed piston in the sleeve, a shaft extending transversely at a right angle through the piston between its heads, a cam track on the inner face of each piston head, an eccentric on the shaft between the heads, and an anti-friction bearing disposed between the eccentric and riding in the tracks to exert a tractive effort for positively reciprocating said piston in the sleeve. 100

5. A pump comprising a pair of complementary casing sections, each section having a centrally arranged sleeve portion and end nipple portions, means for securing the sections together, means locking the nipple portions together, exhaust and intake leads fitted into the nipple locking means, and means in the sleeve for forcing liquid through the casing in a path remote from the joint between the casing sections. 110

6. A pump comprising a casing provided with inlet and outlet leads, said casing also having a sleeve arranged therein, a double headed piston in the sleeve, a shaft passed right angularly through the sleeve and piston, said shaft being journaled for rotation in the casing, an eccentric wheel integrally formed on said shaft and located between the heads of the piston, a bearing around said eccentric wheel, and means in the heads for receiving said bearing to guide the same. 120

125

130

7. A pump comprising a pair of complementary casing sections, each section having a centrally arranged sleeve portion and end nipple portions extending right angularly to the said sleeve portion, means for securing the body of the sections together to form a closed casing, nuts for locking the nipple portions together, exhaust and intake leads mounted in said nuts, and a piston operable in the sleeve for forcing liquid through the 10 casing.
- 8 to the said sleeve portion, means for securing the body of the sections together to form a closed casing, nuts for locking the nipple

Chicago, Illinois, October 16th, 1926.
